UNITED STATES PATENT OFFICE.

WILLIAM MADISON WALKER, OF FULTON, KENTUCKY.

HORSE-DETACHER.

SPECIFICATION forming part of Letters Patent No. 293,125, dated February 5, 1884.

Application filed October 29, 1883. (No model.)

To all whom it may concern:

Be it known that I, WILLIAM M. WALKER, of the city and county of Fulton, and State of Kentucky, have invented a new and useful Improvement in Horse-Detachers, of which the following is a full, clear, and exact description.

The object of the invention is to improve horse detachers, as hereinafter described, and 10 pointed out in the claims.

Reference is to be had to the accompanying drawings, forming a part of this specification, in which similar letters of reference indicate corresponding parts in all the figures.

15 Figure 1 is a side elevation of my improved latch device for detaching the trace and shaft of the carriage. Fig. 2 is a detail of the same in longitudinal section. Fig. 3 is a detail and vertical and transverse section. Fig. 4 is a 20 section of the dash-board, and part of the bottom of the carriage-body, and side elevation of the foot-lever device for working the detacher and the brake, when applied.

I make a malleable-iron bar or plate, *a*, 25 having a latch, *b*, pivoted to one end for securing the trace-loop *c*, to which the part *e* of the trace that is hitched to the carriage is connected, and which is to be released by said latch. The other end of said bar has the 30 buckle *d* pivoted to it, by which the part *f* of the trace is connected that is attached to the hame. Said bar *a* also has the loop *g* at the back, for confining the end of the part *f* of the trace. At the middle of said bar *a* it has a 35 branch, *i*, extending upward, and having the buckle *j* for connecting with the back-band of the harness, and from the lower edge at the same place said bar has a branch, *k*, extending downward, and having the shaft-retaining latch *l* pivoted to its lower end. This latch closes onto the stud *m*, projecting from the front of the upper part of bar *a*, to confine the shaft *n* of the carriage, and is secured by the spring-key *o*, with a spring, *p*, between it 40 and plate *a*, and coiled around stud *m*, to be compressed by said latch, when fastened by key *o*, for pushing off the latch quickly when the key is pulled out, and preventing any failure of the latch to escape. The latch *b* closes

against plate *a* behind latch *l*, and also behind 50 the shaft *n*, which touches the lower edge of said latch *b*, when said shaft is confined by latch *l*, and holds latch *b* closed until the shaft is released. The loop *c* then pulls latch *b* open, and escapes by pulling at *q*, eccentrically to the 55 pivot *s*, which opens latch *b*. The latch *b* has a stud, *t*, that closes into a hole of plate *a* for greater stability while held in latch. The plate *a* also has a loop, *a'*, for attaching the belly-band.

A device of this kind is employed for each trace and shaft, and the spring-keys *o*, for retaining and releasing the latches, are connected by cords *u*, one to each, extending back, through an eye, *v*, in the dash-board *w*, to the foot-lever *x*, pivoted to the bottom of the carriage-body at *y*, and supported on a spring, *z*, suitably for being pressed down by the foot of the driver when it becomes necessary to detach the horse. The spring *z* is coiled around a 70 rod, *b'*, for its support, and said rod is pivoted to the floor of the carriage-body at *c'*, and extends through a hole of the first lever, for being maintained in its proper position.

Having thus described my invention, I claim 75 as new and desire to secure by Letters Patent—

1. The combination of trace-latch *b*, shaft-latch *l*, fastening-stud *m*, and spring-key *o*, with the plate *a*, having trace-buckle *d* and back-strap buckle *j*, substantially as described. 80

2. The combination of trace-latch *b*, shaft-latch *l*, fastening-stud *m*, spring *p*, and spring-key *o*, with the plate *a*, having trace-buckle *d* and back-strap buckle *j*, substantially as described. 85

3. The trace-latch *b*, having stud *t*, in combination with plate *a*, having shaft-latch *l*, said trace-latch *b* being arranged to close behind latch *l*, and be confined by the shaft *n* when it is confined by the latch *l*, substantially 90 as described.

4. The plate *a*, having trace-latch *b*, shaft-latch *l*, trace-buckle *d*, trace-loop *g*, back-band buckle *j*, belly-band loop *a'*, and the latch-stud *m*, combined and arranged substantially as described. 95

5. The combination of the foot-lever *x*, in the body of the carriage, with the spring-keys

o and fastening-studs *m* of a horse-detaching apparatus, for releasing the same, substantially as described.

6. In a horse-detaching apparatus, the 5 spring-keys *o*, for releasing the retaining-latches *b* *l*, having attached cords *u*, extended through the eye *v* of the dash-board, and con-

nected with the foot-lever *x*, pivoted to the floor of the carriage-body at *y*, and supported on the spring *z*, substantially as described.

WM. MADISON WALKER.
